UNITED STATES PATENT OFFICE.

NAPOLEON BÉDARD, OF QUEBEC, QUEBEC, CANADA.

BOILER FURNACE.

Application filed July 18, 1927. Serial No. 206,652.

The invention aims to provide a new and improved boiler furnace of such construction as to effectively consume smoke, thus not only preventing the undesirable discharge of black, soot-laden smoke, but increasing the efficiency of the furnace.

With the foregoing in view, the invention resides in the novel subject matter herein-after described and claimed, the description 10 being supplemented by the accompanying drawing.

Fig. 1 is a longitudinal sectional view showing the invention in connection with a fire tube boiler.

15 Fig. 2 is a vertical transverse section on line 2—2 of Fig. 1.

Fig. 3 is a longitudinal section showing the application of the invention to a water tube boiler.

20 Fig. 4 is a transverse section on line 4—4 of Fig. 3.

B on the accompanying drawing, denotes a boiler of common construction, in connection with which the usual brick-work or 25 other masonry M is used. G denotes the usual grate, A has reference to the ash pit below said grate, and F denotes the fire-box. At the rear end of this fire-box, is a bridge wall 5 of the novel construction herein-after 30 described, and suitable means 6—7 are provided over and behind said bridge wall, forcing the products of combustion to pass first rearwardly above said wall and then downwardly behind the same before they 35 can escape. While the outgoing gases are traveling in this manner, auxiliary air is supplied to them by the means herein-after described, and this air so mixes with unburned fuel units as to cause thorough combustion 40 thereof, thus preventing the discharge of dense smoke and also increasing the efficiency of the furnace and its boiler.

The upper edge of the bridge wall 5 is 45 transversely stepped to provide a rear, relatively high step 8 and a front, comparatively low step 9. A draught inlet slot 10 extends longitudinally of the wall 5 and has its delivery end disposed at the rear portion of the step 9, immediately in front of the 50 step 8. The inlet end 11 of this draught slot may be located at any desired point, determined primarily by the boiler construction, but such end preferably communicates with the ash pit A. For controlling the entrance 55 of air into this slot, I have shown a pivoted damper 12 and an operating rod 13 therefor.

This rod may either be controlled by hand or by some automatic means, as may be desired.

I am aware that prior to my invention, 60 draught inlet passages have been provided in bridge walls, but attention is invited to the fact that the portion of the step 9 between the front of said bridge wall and the discharge end of the slot 10, is rearwardly 65 inclined. I have found this construction to be greatly advantageous over other constructions, and whereas without this inclination, I could not burn as much as 25% of the volume of the smoke, the particular 70 construction shown at the upper end of the bridge wall, enabled me to consume substantially 100%, thus not only preventing the objectionable discharge of smoke into the atmosphere, but tremendously increasing 75 the efficiency of the furnace and associated boiler. Hence, it is in this improved construction at the upper edge of the bridge wall, that the gist of the present invention resides. In other regards, the furnace 80 construction may be conventional and varied in numerous ways. It will also be understood that the proportions of parts may be changed according to the sizes and types of furnaces with which the invention is used, 85 and that the upper edge of the bridge wall may either be straight or curved, as will be clear from a comparison of Figs. 2 and 4.

I claim:

1. In a boiler furnace, a grate, a bridge wall at the rear end thereof, the upper edge of said bridge wall being transversely stepped to provide a rear relatively high step and a front comparatively low step, said front step having an upwardly and rearwardly inclined surface, said bridge wall having a vertical, longitudinal draught inlet slot which opens upwardly through the rear portion of said comparatively low step, and has its lower end turned forwardly and opening into the ash pit of the furnace, a damper to control the admission of air into said lower end of the slot, a vertical wall behind and spaced from said bridge wall and having a passage in its lower portion, 100 and a horizontal upper wall projecting from the upper end of said vertical wall and over said bridge wall and the space between said walls.

2. In a boiler furnace, a grate, a bridge wall at the rear thereof, the upper edge of said bridge wall being transversely stepped

to provide a rear relatively high step and a front comparatively low step, said front step having an upwardly and rearwardly inclined surface, the rear side of said bridge wall being extended rearwardly at its lower end, said extension having its upper surface curved rearwardly and downwardly to direct the currents of smoke and air rearwardly after passing over the bridge wall, said bridge wall also having a vertical longitudinal draught inlet slot which opens upwardly through the rear portion of said comparatively low step, and has its lower end turned forwardly and opening into the ash pit of the furnace, a damper to control

the admission of air into said lower end of the slot, a vertical wall behind and spaced from said bridge wall and having a passage in its lower portion into which the rearwardly and downwardly extended rear side of the bridge wall projects and an inclined upper wall on the upper end of said vertical wall and projecting rearwardly a short distance therefrom and forwardly over the bridge wall, the space between said walls and over the entire fire box of the furnace.

In testimony whereof I have hereunto affixed my signature.

NAPOLÉON BÉDARD.
